CAR COUPLER MECHANISM

George T. Johnson and Harry H. Wolfe, Columbus, Ohio, assignors to The Buckeye Steel Castings Company, Columbus, Ohio

Application November 8, 1930, Serial No. 494,415

1 Claim. (Cl. 213—65)

This invention relates to improvements in car coupler mechanism having draft gears of the double-acting type.

The selective travel or double-acting gear is a type that has recently come on the market, and it functions somewhat differently from the ordinary draft gear. We have devised an improved mechanism of this kind.

In freight car service, the greatest forces on the couplers are the buffing forces, and a double-acting draft gear has practically twice the capacity in buff as it has in pull.

The primary object of the present invention is to provide a novel coupling mechanism in which the yoke and housing of the double-acting draft gear are formed of a single piece metal casting.

Another object is to provide such a mechanism in which the front draft lugs are omitted.

A still further object is to furnish a coupler mechanism of the double-acting type, which is of stronger, lighter and more compact construction than those heretofore known.

With the foregoing objects outlined and with other objects in view which will appear as the description proceeds, the invention consists in the novel features hereinafter described in detail, illustrated in the accompanying drawings, and more particularly pointed out in the appended claim.

30 In the drawings,

Fig. 1 is a horizontal sectional view partly in top plan, of a coupler mechanism equipped with our improvements.

Fig. 2 is a vertical sectional view of the same, partly in elevation.

Fig. 3 is a transverse sectional view on the line 3—3 of Fig. 2, and with the rear key omitted.

Referring to the drawings, 1 designates the improved yoke, which is tubular for the greatest portion of its length, as shown at 2, to form the draft gear housing.

3 designates the rear key which is horizontally arranged and passes through the side sills, yoke and draft gear.

45 4 designates the front coupler key within is also horizontally arranged.

The front follower is shown at 5, and the rear follower is indicated at 6. These followers, as well as the draft gear and yoke are positioned 50 between the side sills 7, and the latter are tied together by a center brace 9 which is integral with the rear draft lugs 8, against which the follower 6 bears.

A striker casting 10 joins the front ends of the 55 sills and receives coupler shank 11 which has a

slot 12 through which the key 4 extends. The key also extends through slots 13 in the sides of the yoke and slots 14 in the sills, and it will be noted that the slot 12 is of about the same width as the key, while the slots 13 are of greater length than the key and bear against the latter only at their front ends. The slots 14 are considerably wider than the slots 13, and the key does not bear against the ends of the slots 14.

Slots are formed in the sides of the draft gear 10 housing, as shown at 15.

Draft lugs or cheek plates 16 are firmly united with the outer sides of the sills, and have slots 16a of about the same width as the slots 15. The key 3 bears at its front edge against the front ends 15 of the slots 16a.

The springs or front yielding elements are shown at 18, and the rear yielding elements at 18a. The front yielding elements bears at one end upon the front follower 5 and at its rear end 20 upon a second follower 19 abutting the key 3. The rear yielding element 18a bears at its rear end upon the follower 6, while its front end abuts a second follower 19a. The followers 19, 19a abut the key and reciprocate with the latter relative 25 to the yoke. During pull, the coupler shank 11 exerts a pulling force on the yoke and draft gear housing 2 by means of the horizontal key 4. The yoke and follower 6 compress the rear yielding element 18a against the follower 19a, which is 30 held by the key 3, and through the latter, transmits the draft forces to the center sill 7. During buff, both the front and rear yielding elements are compressed against the rear follower 6 which transmits the buffing forces through the 35 draft lugs 8 to the center sills. The key 3 and followers 19 and 19a move rearwardly a distance equal to the compression of the rear yielding element.

While it is not our intention to limit ourselves 40 to any one type of yielding elements, a simple type of yielding elements or draft gear which can be used with the housing, is illustrated in the drawings. Many other types of yielding elements could be used with the housing, and also 45 by slight changes in contour of the inside surface of the housing, other types of draft gear can be used.

In operation, when a pull is exerted by the coupler shank 11, the key 4 will cause the yoke 1 50 to move forwardly, and this will result in forward movement of the follower plate 6 by the rear end of the yoke, and the rear portion of the draft gear will be compressed against the key 3, which will in turn bear against the lugs 16 and trans- 55

mit the pulling movement to the car sills 7. During such movement, the follower plate 6 and yoke will travel forward a distance equal to the compression of the rear portion of the draft gear.

5 In buff, the coupler shank 11 bears against the follower 5, as shown at 17, and while the follower is moved the distance indicated at B, the yoke will be caused to move rearwardly and the follower 5, through the instrumentality of the 10 front yielding element, will force the key 3 to compress the draft gear against the follower plate 6, so that the gear will be further compressed equal to the distance A, and the rear end of the yoke will come into the dotted line position 15 shown at C, when the gear is fully compressed.

15 The invention has the advantage of reducing the weight of the yoke and gear assembly, due to the fact that the yoke straps form a part of the gear housing. Furthermore, a construction 20 of this character can occupy a smaller space than if the housing and yoke were separate elements.

25 In the claim, "draft gear housing" means a casing in which is assembled the usual springs and friction elements which make up a draft gear. It is a container for these parts, and essential to the operation as a draft gear.

30 From the foregoing it is believed that the construction, operation and advantages of the invention may be readily understood, and it is manifest that changes may be made in the details disclosed, without departing from the spirit of the invention, as described in the claim.

35 What is claimed and desired to be secured by Letters Patent is:

In combination, draft sills, a unitary yoke and draft gear housing arranged between said draft sills and adapted to move forwardly and rearwardly in unison, stationary stops at the rear end of the combined yoke and housing, front and rear followers mounted for reciprocation in the combined yoke and housing longitudinally of the latter, rear yielding elements in the combined housing and yoke for normally holding the rear follower in contact with said stops, front yielding elements for normally holding the front follower in contact with portions of the combined yoke and housing, means separating the front yielding elements from the rear yielding elements and operatively connected to said sills for 15 limiting forward movement of the rear yielding elements during pull while said rear yielding elements are compressed, and for compressing said rear yielding elements during buff while the rear stops restrict rearward movement of the rear 20 follower, a coupler shank, a second horizontal key connecting said shank to the forward end of the unitary yoke and draft gear housing and sills, said second key being movable with the shank relatively to the sills during both buff and draft 25 and relatively to the yoke and draft gear housing during buff only, said shank being engageable with the front follower and adapted during buff to move the front follower rearwardly and thereby cause the front yielding elements to be compressed, and the front yielding elements to in turn shift said means rearwardly.
